(57) **CLAIM**

The ornamental design for an angled bicycle rack, as shown and described.

DESCRIPTION

FIG. 1 is a front elevational view of the angled bicycle rack. FIG. 2 is a back elevational view of the angled bicycle rack. FIG. 3 is a top plan view of the angled bicycle rack. The bottom plan view is not normally visible when in use and therefore is not shown.

FIG. 4 is a left elevational view of the angled bicycle rack. FIG. 5 is a right elevational view of the angled bicycle rack. FIG. 6 is a front perspective view of the angled bicycle rack. FIG. 7 is a back perspective view of the angled bicycle rack; and,

FIG. 8 is a front perspective view of the angled bicycle rack containing bicycles. The bicycles contained in the rack are shown in broken lines and are not part of the claimed design.
